US00D942950S

(12) **United States Design Patent** (10) **Patent No.:** **US D942,950 S**
(45) **Date of Patent:** **** Feb. 8, 2022**

(54) **ROLL-UP EXTENSION CORD**

(71) Applicant: **Les extensions Rollup Inc.**, Montréal (CA)

(72) Inventors: **Samuel Archambault**, Laval (CA); **Julien Croteau**, Montreal (CA)

(73) Assignee: **LES EXTENSIONS ROLLUP INC.**, Montréal (CA)

(**) Term: **15 Years**

(21) Appl. No.: **29/715,306**

(22) Filed: **Nov. 30, 2019**

(30) **Foreign Application Priority Data**

May 30, 2019 (CA) 187779

(51) **LOC (13) Cl.** **13-03**

(57) **CLAIM**

The ornamental design for a roll-up extension cord, as shown and described.

DESCRIPTION

FIG. 1 is a perspective view of a roll-up extension cord, FIG. 2 is a front view thereof,

FIG. 3 is a rear view thereof,

FIG. 4 is a right side view thereof,

FIG. 5 is a left side view thereof,

FIG. 6 is a top view thereof; and,

FIG. 7 is a bottom view thereof.

The broken lines showing the recess on the female plug illustrate a portion of the roll-up extension cord that form no part of the claimed design.

1 Claim, 7 Drawing Sheets
